LINE TYPE PRESSURE RESPONSIVE
MICROPHONE

Harry F. Olson, Princeton, and John Preston,
Metedeconk, N. J., assignors to Radio Corpora-
tion of America, a corporation of Delaware

Application June 22, 1950, Serial No. 169,574

8 Claims. (Cl. 179—115.5)

1

This invention relates to sound translating apparatus, and more particularly to an improved line type, pressure responsive microphone.

In the broadcast field where sound apparatus is often close to the sound source, there is a need for an instrument of a size such that it is relatively inconspicuous and yet has excellent sound reproducing qualities. For example, in television broadcasting where the microphone is located close to a performer, it should not obstruct the view of the performer from the camera. For some of these applications, the pressure type microphone is considered most suitable because the shape of the response frequency characteristic of this type of microphone does not vary with the distance from the sound source.

It is a primary object of the present invention to provide an improved microphone which will not materially interfere with the view of a performer when it is closely disposed in front of him.

Another object of the present invention is to provide an improved, small, pressure type microphone having excellent sound reproducing qualities and which can be disposed remotely from the sound pick up point.

It is also an object of the present invention to provide a small microphone having a high order of sensitivity over a wide range of useful sound frequencies which is particularly useful in motion picture, television, or other stage productions where it is desired to keep the microphone as inconspicuous as possible.

Another object of the present invention is to provide a pressure responsive, electroacoustic translating device which is highly efficient and so compact in structure that it is easily portable and relatively inconspicuous.

In accordance with the present invention, the microphone comprises a magnetic field structure defining an air gap within which a flexible, ribbon or strip conductor is mounted for vibration in well known manner. Long tubes or conduits are arranged to form chambers on opposite sides of the air gap thereby to isolate the strip from the sound pick up point. The tube on one side of the strip comprises a sound inlet pipe for transmitting sound waves to the conductive strip. The cross sectional area throughout the length of the sound transmitting tube is made substantially equal to the cross sectional area of the air gap so that the surge acoustical resistance of the sound transmitting tube is substantially equal to the terminating acoustical resistance of the air gap. The other

2

tube comprises a pipe of relatively infinite length for dissipating substantially completely the sound waves transmitted into it. In order to accentuate the high frequency response, a small horn may be provided for mounting on the open end of the sound inlet pipe.

The novel features characteristic of the present invention, as well as additional objects and advantages thereof, will be better understood from the following detailed description when read in connection with the accompanying drawing, in which:

Figure 1 is a front elevation of one form of microphone in accordance with the present invention,

Figure 2 is an enlarged, central longitudinal section of the microphone shown in Figure 1,

Figure 3 is an enlarged, side view of the connector shown in Figure 2 between the diaphragm chamber and the acoustic labyrinth.

Figure 4 is a front view of the connector illustrated in Figure 3.

Figure 5 is an end view of the connector shown in Figures 3 and 4, looking in the direction of the arrows 5—5 in Figure 4, and

Figure 6 is a view similar to Figure 5 looking in the direction of the arrows 6—6 in Figure 4 and showing the position of the conductive strip with respect to the rectangular opening of the connector.

Referring more particularly to the drawing, wherein similar reference characters designate corresponding parts throughout, there is shown a microphone 1 for converting sound waves into corresponding electrical variations in accordance with a preferred embodiment of the present invention. The microphone 1 comprises a light weight housing 3 in which are mounted a sound translating unit 5, a sound transmitting tube 7, an acoustic labyrinth 9, and an output transformer unit 11.

The sound translating unit 3 is of the pressure responsive type and includes a flexible ribbon diaphragm or strip 13 mounted in a magnetic field for vibration in response to sound waves impinging thereon. The ribbon diaphragm 13 comprises a corrugated strip of electro-conductive material, such as aluminum foil. The magnetic field is provided by a structure 50 of generally cylindrical shape and comprises a pair of semicylindrical permanent magnets 15, an annular base plate 17, and a pair of semicylindrical pole pieces or plates 19. Each of the magnets 15 has one end thereof fastened to the base plate 17, and they are arranged so

that they will be disposed in spaced apart relation with their flat sides facing each other and substantially parallel. The pole pieces 19 are mounted on the opposite ends of the magnets with their plane edges or faces disposed in closely spaced, parallel relation to provide an elongated air gap of rectangular cross section therebetween. The ribbon diaphragm 13 is fastened at the ends thereof by suitable clamping means (not shown) of a kind which will support the ribbon centrally within the air gap with small clearance between the side edges of the ribbon and the adjacent pole piece plane edges so that it divides the air gap chamber into separate compartments. Thus, the ribbon diaphragm is supported within a magnetic field in the air gap for vibration in well known manner.

The sound transmitting tube 7 comprises an elongated pipe or conduit having an unobstructed bore of relatively small circular cross section. One end of the pipe is open to the ambient for picking up sound waves for transmission through the pipe to the ribbon diaphragm 13. A portion of the opposite end of the pipe defines a throat 7a the cross section of which varies from a circular shape having a diameter corresponding to that of the pipe 7 to a rectangular shape at the end of the pipe adjacent the air gap. The shape of the pipe throat portion 7a is such that it converges from its upper end to its lower end in one plane, and diverges from its upper end to its lower end in a plane normal to the first mentioned plane considered in a direction along the longitudinal axis of the transmitting tube or pipe 7. The end of the pipe throat portion defines a rectangular orifice which opens into and surrounds the air gap so that it forms a closed chamber. Thus, the pipe 7 closes off the air gap on one side of the conductive ribbon 13 directly from the ambient.

In order to hold the throat end of the pipe in alignment with the air gap and to assist in supporting the pipe 7 so that the longitudinal axis thereof passes through the air gap at right angles to the longitudinal and transverse axes of the ribbon 13, an annular plate 21 is fastened to the throat end. Insulating material 23 is disposed between the plate 21 and the pole pieces 19 and the plate is secured to the pole pieces 19 by any suitable fastening means.

Coupled to the rear of the air gap or diaphragm chamber on the side opposite the sound transmitting pipe 7 is an acoustic labyrinth 9. The acoustic labyrinth comprises a pipe of relatively great length so that it functions as an acoustical resistance terminating the back of the ribbon 13 to make it responsive to the pressure component of a sound wave in well known manner. The pipe or conduit 9 is made in the form of a single cylindrical block or unit having a plurality of longitudinally disposed, communicating tubes or bores 25. The bores 25 are interconnected to form a continuous passage so that the unit comprises an acoustic labyrinth of the type more particularly shown and described in Olson Patent No. 2,271,988.

In order to close off the air gap at the rear of the ribbon 13 and connect it to the acoustic labyrinth 9, a labyrinth connector 27 is provided. The connector 27 is constructed similarly to the throat portion of the pipe 7 so that a rectangular orifice 29 is defined at one end and a circular orifice 31 at the opposite end. The rectangular end of the connector 27 abuts the pole pieces 19 and is cemented or otherwise fastened thereto to hold the

rectangular opening in alignment with and to close off the air gap. The opposite end communicates with the central bore of the acoustic labyrinth 9 through an opening 33 provided in the base plate 17.

5 The labyrinth connector 27 and the acoustic labyrinth bores 25 are filled with suitable acoustic damping material 35 such as loosely distributed hair felt, or the like, thereby to simulate the 10 effect of a loading pipe of infinite length, as described in the above mentioned Olson patent.

By making the surge acoustical resistance of the line or sound transmitting pipe 7 coupling free space to the ribbon 13 substantially equal to 15 the terminating acoustical resistance at the air gap, there will be substantially no deterioration in the response frequency characteristic of the microphone 1 resulting from the line coupling. This has been accomplished by making the cross 20 sectional area of the bore of the sound transmitting tube 7, throughout the length thereof, substantially equal to the area of the air gap in a plane corresponding with that including the longitudinal and transverse axes of the ribbon 13.

25 The output transformer unit 11 is mounted below the acoustic labyrinth 9 and comprises an output transformer 37 mounted in any convenient manner within a casing 39. An opening 41 in the upper wall of the casing 39 is in registry with 30 another opening 42 in the bottom of the acoustic labyrinth 9 for communication with the continuous pipe. Thus, the effective length of the acoustic labyrinth is extended by the space within the transformer casing 39. The transformer casing 35 is also filled with acoustic damping material of the kind disposed in the bores 25.

30 The various parts or units are arranged to slidably fit in the microphone cylindrical housing 3 in close fitting relation with the interior walls 40 thereof. The parts are disposed one above the other starting with the transformer unit 11 at the lower end of the housing. The acoustic labyrinth unit 9, the sound translating unit 5 and the sound transmitting pipe 7 are mounted above the transformer casing 39 in the order named.

45 The housing 3 is closed at the bottom end thereof and provided with a suitable coupling 43 for connecting the microphone 1 to an external electrical circuit. The opposite end of the microphone housing 3 is tapered to conform substantially to a diameter slightly larger than that of the sound transmitting pipe 7 so that it forms a long, slender tube.

50 In case it is desirable to accentuate the high frequency response, this can be done by coupling a small horn 45 to the open end of the sound transmitting tube 7. The small horn 45 is tapered outwardly toward its free end at a rate of flare which will provide the high frequency response 55 characteristic desired. For the purpose of preventing foreign matter from entering the sound transmitting tube, a screen 47 is mounted on the end of the sound transmitting tube.

60 From the foregoing description, it will be apparent that the present invention provides a small, compact, light weight microphone which permits the major sound translating apparatus to be isolated from the sound pickup point. The portion of the microphone which picks up and transmits sound waves to the air gap can be made relatively small in diameter so that when it is disposed close to a sound source it will be relatively inconspicuous.

65 Although only a single, preferred embodiment 70 of the present invention has been illustrated and

described herein, it should be obvious to those persons skilled in the art that modifications and changes are possible within the spirit of the invention. For example, the sound transmitting tube need not be straight but may have the sound pickup end angularly disposed with respect to the body of the instrument. In such a case, the instrument may be mounted on its side on a support for placing it on a desk or table with the tube pickup end disposed upwardly. Other changes of like nature will undoubtedly suggest themselves to those skilled in the art. Therefore, it is desired that the particular form of the present invention described herein shall be considered as illustrative and not as limiting.

What is claimed is:

1. An electroacoustical translating device comprising a magnetic field structure including means providing a closed chamber, sound transmitting conduits disposed on opposite sides of and opening into said chamber, and a flexible, electro-conductive ribbon diaphragm extending across said chamber substantially cutting off communication between said conduits, said conduits being substantially equal in cross sectional area at points therein in proximity to said chamber, said cross sectional area being substantially equal to the area of said chamber in the plane of said ribbon diaphragm, one of said conduits having an unobstructed bore terminating in an open end remote from said chamber for picking up sound waves for transmission through said one conduit to said ribbon diaphragm, the cross sectional area of said bore throughout the length thereof being substantially equal to said chamber area.

2. The invention set forth in claim 1 and wherein a relatively small horn is disposed on said one conduit open end for accentuating response to high frequency sound waves.

3. An electroacoustic translating device comprising a magnetic field structure including spaced magnetic pole pieces defining an elongated air gap, an elongated conduit having an unobstructed bore throughout a greater portion of the length thereof for directing sound waves to said air gap, one end of said conduit abutting said pole pieces and defining a throat portion which converges in one plane toward the end thereof adjacent said air gap and diverges in a plane normal to said one plane toward said end adjacent said air gap considered in a direction along the longitudinal axis of said conduit, the end of said throat portion abutting said pole pieces defining an elongated slot opening into said air gap, an elongated strip of flexible conducting material in and extending lengthwise of said slot with relatively small clearance between each side edge thereof and the pole piece adjacent thereto, the cross sectional area of said bore throughout the length of said conduit being substantially equal to the area of said air gap in the plane including the longitudinal and transverse axes of said elongated strip, and means including said elongated conduit for closing off said air gap directly from the ambient.

4. An electroacoustic translating device comprising a magnet having spaced apart pole pieces providing an air gap therebetween, a conduit having its longitudinal axis passing through said air gap for directing sound waves to said air gap, one end of said conduit abutting said pole pieces to close off said air gap directly from the ambient from one side thereof, said conduit opening directly into said air gap through an elongated,

rectangular orifice of substantially the same cross sectional area as said air gap, an elongated strip of flexible conducting material in and extending lengthwise of said air gap with its side edges in closely spaced relation to said pole pieces, said conductive strip having its longitudinal and transverse axes extending normal to said conduit longitudinal axis, the cross sectional area of said conduit throughout the length thereof being substantially equal to the cross sectional area of said air gap in the plane including the longitudinal and transverse axes of said conductive strip, and means closing off the remainder of said air gap from the ambient.

5. An electroacoustic translating device comprising spaced magnetic pole pieces defining an elongated air gap, a flexible elongated strip of conducting material mounted between said pole pieces centrally within said air gap for vibratory movement in response to sound waves impinging thereon, said conductive strip being disposed with relatively small clearance between the side edges thereof and the pole pieces adjacent thereto, a conduit the longitudinal axis of which passes through said air gap at right angles to the longitudinal and transverse axes of said strip, an end portion of said conduit comprising a throat having an open end abutting said pole pieces to close off said air gap on one side of said conductive strip directly from the ambient, said conduit having an unobstructed bore throughout the length thereof communicating with said throat, the cross sectional area of said bore being substantially equal to the cross sectional area of said air gap in a plane normal to said conduit longitudinal axis, and means closing off said air gap on the opposite side of said conductive strip directly from the ambient.

6. The invention set forth in claim 5 wherein said means closing off the opposite side of said air gap provides an acoustical resistance terminating the back of said conductive strip and comprises a pipe of relatively great length, the cross sectional area of said pipe being substantially equal to that of said unobstructed bore.

7. An electroacoustic translating device comprising a closed diaphragm chamber, a diaphragm comprising a thin, corrugated strip of conducting material mounted in said chamber for vibration in response to sound waves impinging thereon, a sound transmitting pipe having an unobstructed bore of relatively great length open at one end and in direct open communication at its opposite end with said chamber, the cross sectional area of said bore throughout the length thereof being substantially equal to the cross sectional area of said diaphragm chamber in the plane of said strip, a second pipe of relatively great length in direct open communication at one end thereof with said diaphragm chamber, the cross sectional area of said second pipe at said open end being substantially equal to the cross sectional area of said first mentioned pipe, sound absorbing material in said second pipe for dissipating substantially completely sound waves which pass into said pipe, and means for converting vibrations of said diaphragm into electrical oscillations.

8. An electroacoustic translating device comprising magnetic means providing a magnetic field within a closed chamber, a flexible, electro-conductive member mounted in said chamber for movement in response to sound waves impinging thereon, said flexible member being disposed

centrally in said chamber and dividing said chamber into separate compartments, a tubular member opening directly into one of said compartments for directing sound waves to one side of said flexible member, said tubular member being so dimensioned that the surge acoustical resistance thereof is substantially equal to the terminating acoustical resistance of said chamber, and means communicating with the other of said compartments providing an acoustical resistance terminating the side of said flexible member facing said other compartment whereby said flexible member is responsive to the pressure component of a sound wave.
